UNITED STATES PATENT OFFICE.

CHARLES H. METZ, OF WALTHAM, MASSACHUSETTS, ASSIGNOR TO THE WALTHAM MANUFACTURING COMPANY, OF SAME PLACE.

DESIGN FOR A CROWN FOR BICYCLE-FORKS.

SPECIFICATION forming part of Design No. 26,764, dated March 16, 1897.

Application filed July 20, 1896. Serial No. 599,976. Term of patent 14 years.

To all whom it may concern:

Be it known that I, CHARLES H. METZ, of Waltham, in the county of Middlesex and State of Massachusetts, have invented and produced a new and original Design for Crowns for Bicycle-Forks; and I hereby declare that the following is a specification of the same, reference being had to the accompanying drawings, forming part hereof.

Figure 1 represents an elevation of a crown for bicycle-forks, illustrating my new design. Fig. 2 represents a plan view of the same.

The leading features of the design consist in the configuration of the bicycle-crown, as shown in the drawings.

In the drawings, 5 5 indicate end members,

from which the inclined members 6 6 extend, these being connected by the central member 7. From this member 7 extend the outwardly-inclined members 8 8, having the straight ends 9 9, which lie parallel to the members 5 5. From the ends 9 9 extend the inwardly and upwardly-inclined members 10 10, connected by the member 11.

What I claim is—

The design for a crown for bicycle-forks as herein shown and described.

CHARLES H. METZ.
